UNITED STATES PATENT OFFICE.

GEORGE WASHINGTON PALMER, OF NEW YORK, N. Y.

DESIGN FOR A HANGER FOR WASHING-MACHINES.

SPECIFICATION forming part of Design No. 31,634, dated October 10, 1899.

Application filed August 16, 1899. Serial No. 727,449. Term of patent 7 years.

To all whom it may concern:

Be it known that I, GEORGE WASHINGTON PALMER, a citizen of the United States, and a resident of New York, (Brooklyn,) county of 5 Kings, and State of New York, have invented and produced a new and original Design for a Hanger for Washing-Machines, of which the following is a specification, reference being had to the accompanying drawings, forming 10 a part thereof, in which similar letters and figures of reference indicate corresponding parts.

Figure 1 is an edge view of a hanger for washing-machines, showing my new design; 15 and Fig. 2 is a plan view.

As shown in the drawings, the leading or material feature of my design consists of a flat body A, having an arched extension B at its end, said body being provided with parallel longitudinal slots or openings 1 and a recess 2, which is extended longitudinally from the rear edge toward the front edge centrally of the body and intermediately between the slots or openings 1. The rear edges of the 25 said recess are curved, as at 3.

The arched extension B of the plate A is

projected at an angle and extends transversely across the same. The flat upper portion 8 of the arched portion B of the device is extended upon a horizontal plane parallel 30 with the body A, and the downwardly-extended portion 9 is parallel with the upwardly-extended portion 4. Across the top of the arched portion B is a transverse rib C of rectangular contour, which is at right angles with 35 the horizontal portion 8.

The various surfaces of the body and arched angular extensions are flat or smooth, as shown.

Having thus described my invention, what 40 I claim as new, and desire to secure by Letters Patent, is—

The design for a hanger for washing-machines, substantially as shown and described.

In testimony that I claim the foregoing as 45 my invention I have signed my name, in presence of two witnesses, this 14th day of August, 1899.

GEORGE WASHINGTON PALMER.
